UNITED STATES PATENT OFFICE.

CHARLES E. JOHNSON, OF MUSKEGON, MICHIGAN.

ATTACHMENT FOR PISTON-RING-GRINDING MACHINES.

Application filed December 24, 1919, Serial No. 847,167. Renewed April 17, 1922. Serial No. 553,923.

To all whom it may concern:

Be it known that I, CHARLES E. JOHNSON, a citizen of the United States of America, residing at Muskegon, in the county of Muskegon and State of Michigan, have invented certain new and useful Improvements in Attachments for Piston-Ring-Grinding Machines; and I do hereby declare the following to be a full, clear, and exact description of the invention, such as will enable others skilled in the art to which it appertains to make and use the same.

This invention relates to an attachment designed to be applied to grinding machines, particularly for the purpose of facilitating the grinding of piston rings on the faces thereof. It is a primary object and purpose of the invention to construct an attachment by means of which piston rings may be taken one at a time from a quantity of rings and carried to proper position on a magnetic clutch, to which they may be fixed by energizing the chuck, after which the same may be ground by carrying a rapidly moving grinding wheel across the same, it being understood that the chuck likewise is rotating at comparatively high speed during the grinding operation. A further object of the invention is to construct a very simple yet thoroughly practically operative attachment of this kind which, when applied to grinding machines, makes it possible to grind piston rings without the employment of highly skilled labor as has been universally necessary before.

For an understanding of the invention and the constructions embodying the same, reference may be had to the following description taken in connection with the accompanying drawings, in which;

Fig. 1 is a partial sectional and side elevation of a grinding machine having my invention applied thereto.

Fig. 2 is a plan view thereof.

Fig. 3 is a fragmentary vertical section taken substantially on the line 3-3 of Fig. 2, and

Fig. 4 is a horizontal section taken substantially on the line 4-4 of Fig. 1.

Like reference characters refer to like parts in the different views of the drawing.

The invention is designed to be applied to a grinding machine, the frame or pedestal of which is indicated at 1. At the upper

side of said pedestal a grinding wheel 2 is mounted on a suitable shaft which may be

driven through a belt passing around a drive pulley 3 on the shaft. Any other means of driving the grinding wheel may be used. Said grinding wheel may be moved back and forth with respect to the pedestal through the operation of a wheel 4 so as to carry the grinding wheel over a magnetic chuck 5 located underneath the grinding wheel. This chuck may be driven in any suitable manner so as to turn about a vertical axis, gearing 6 being used to transmit motion from the cone drive pulley, indicated in Fig. 1, to the clutch.

A bracket 7 is attached to the pedestal to one side of the magnetic chuck, the same being provided with a long sleeve in which a shaft 8 is mounted vertically for rotation. Adjacent the upper end of the shaft a thin circular metal plate 9 is secured in which, in the construction shown, four openings 10 are made at equally spaced distances from each other. The plate 9 passes just above and across the upper side of the chuck 5 and also above a horizontal fixed plate 11 which may be supported in any desired manner as by attachment to the bracket 7. Plate 11 comes closely adjacent the side of the chuck 5 and at one edge is curved to conform thereto, as indicated in dotted lines in Fig. 2. A bracket 12 is secured to the plate 11 and is turned in above the circular plate 9 for a distance terminating in an upwardly extending trough 13 which has two sides located at an angle to each other as shown. The trough serves as a guide for a quantity of piston rings 14 which may be placed therein, one above the other being properly positioned by their engagement against the sides of the trough.

At the lower end of the rod 8, a disk 15 is secured having four notches 16 in its edges in any of which a spring actuated pin 17 is adapted to engage. The notches 16 are so positioned with respect to the openings 10 in plate 9 that whenever the pin 17 is engaged in a notch, one opening 10 comes directly beneath the column of piston rings located in the guide trough 13. Another of the openings is positioned so that its center coincides substantially with the vertical axis of the magnetic chuck 5 while the remaining openings are located to one side of the plate 11 and the magnetic chuck as shown in Fig. 2.

In operation the operator grasps the plate 9 and turns it so that the pin 17 disengages

from one notch 16 and seats in the next succeeding notch. The plate is turned in a clockwise direction and the lowermost ring is taken from the column of rings located 5 in the guide trough 13 and carried to the chuck 5. The chuck is then energized so that the ring is attached to the chuck by magnetic attraction. It is evident that with the grinding machine in operation the chuck 10 and ring turn rapidly and when the grinding wheel is brought across the ring, the upper face of the ring is ground. The chuck may then be de-energized and the plate 9 turned again one quarter of a revolution 15 whereupon the ground ring, as soon as it leaves the clutch, drops from the opening 10 to any suitable receptacle or guide therefor which may be provided to receive it, and the next lowermost ring is moved from 20 the column of rings to the chuck whereupon the grinding operation may be repeated. The operation may be repeated indefinitely 25 as long as there are rings to be ground.

The construction is simple, with it the 30 rings may be properly positioned on the chuck automatically with the turning of the plate 9 and the employment of skilled labor is more or less eliminated, so far as grinding the faces of piston rings is concerned. 35 The detail of construction of the ring grinder are not fully set forth inasmuch as the same are not novel with me and form no part of the present invention. The number of openings in plate 9 and notches in 40 disk 15 may be varied and various other changes in minor detail of construction resorted to without departing from the invention which is defined in the appended claims and I consider myself entitled to all modifications of structure which fall within the scope of said claims.

I claim:

1. In combination, a support, a chuck having a horizontal upper face, means for 45 mounting said chuck to turn about a vertical axis, a plate provided with a plurality of ring receiving openings mounted to turn about a vertical axis, said plate extending over the face of the chuck, means for 50 supporting a column of rings one over the other whereby the lowermost of said rings may be received in an opening in the plate, and means for yieldingly stopping the plate in any one of a plurality of positions in any 55 of which positions one of the openings in the plate is located to receive the lowermost

of the rings in said column of rings and another of said openings in the plate is located directly over the upper face of the chuck, substantially as described. 60

2. In combination, a support, a chuck mounted on said support to turn about a vertical axis, a bracket attached to the support, a vertical shaft mounted for rotation on the bracket, a thin plate attached at the upper end of the shaft and formed with a plurality of openings therein each adapted to receive a ring, a disk attached to the lower end of the shaft and provided with a plurality of notches in its edges one for each opening in the plate, a spring pressed pin adapted to seat in any of said notches in the disk, a supporting plate located underneath the first plate and directly over which one of the openings in said first plate comes when said pin is seated in a notch in the disk, and a vertical trough shaped guide disposed over the first plate and carried by said supporting plate, said guide being adapted to position a column of rings located one over the other so that the lowermost ring of the column may pass into an opening in the first plate and be carried to and above the chuck on rotative movement of said vertical shaft about its axis, substantially as described. 70

3. In combination, a support, a chuck having a horizontal upper face, means for mounting said chuck to turn about a vertical axis, a plate provided with a plurality of ring receiving openings mounted to turn about a vertical axis, said plate extending over the upper face of the chuck, a supporting member attached to the support under the plate and extending beyond the edge of the plate, a vertical trough having two angularly positioned sides and open at one side supported by said supporting member in a position over and slightly spaced at its lower end from the plate, said trough being adapted to freely receive rings at its open side whereby a vertical column of rings may be guided by the trough, and a grinding wheel adapted to grind rings fixed on the chuck and which are successively carried to the chuck from the column of rings by said plate, the openings in said plate successively receiving the lowermost ring of the column, substantially as described. 80

In testimony whereof I affix my signature.

CHARLES E. JOHNSON.
